UNITED STATES PATENT OFFICE

EDWARD HENRY PHILLIPS, OF KENSINGTON, AUSTRALIA, ASSIGNOR TO PHILLIPS VOLATILISOR SYNDICATE COMPANY, LIMITED, OF SYDNEY, NEW SOUTH WALES, AUSTRALIA, A COMPANY OF NEW SOUTH WALES

CARBURETOR

Application filed January 11, 1928, Serial No. 246,057, and in Australia February 18, 1927.

This invention relates to the volatilization of liquid fuels its object being to provide a simple and efficient carburetor.

Many appliances have hitherto been invented and used for the purpose of gasifying liquid fuels such as petrol and these appliances have been more or less efficient. For some purposes it is only necessary to produce what is known as a weak mixture at a comparatively slow speed, but for the purpose of power production the appliances used for the gasification of the liquid fuel must be capable of producing the gas rapidly or slowly and in variable degrees of richness. Whilst many of the carburetors that are now used for power production give satisfactory results few if any of them produce what might be called a dry gas, or in other words a percentage of the fuel is not gasified at the proper time and in some instances enters the engine cylinders thereby causing carbonization and of course resulting in wastage of fuel. The general practice adopted is to cause the current of air induced by each suction stroke of the engine to be drawn through a mixing chamber wherein a predetermined quantity of liquid fuel is projected, induced or contained so that the air is brought into contact with a jet or over the surface of the liquid fuel. At times the atmospheric conditions are such that the gas mixture thus obtained is not sufficiently rich and supplementary means are adopted for the purpose of strengthening the mixture.

When a relatively rich mixture is required it is not sufficient to pass the air through the liquid fuel in the form of large bubbles, as the superficial area of contact between the air and the liquid is not large enough to bring about the required amount of vaporization. According to my invention I employ a container into which the liquid fuel is controllably fed, and which is connected to the engine intake so that each suction stroke of the engine will create a partial vacuum within the container; at the bottom of the container is a chamber shaped so that it will be submerged in the liquid fuel and having a number of perforations preferably in the top thereof. This chamber is connected to one

end of a pipe through which air may be controllably drawn into the chamber, such air passing thence through the perforations, in the top of the chamber, upwardly through the liquid fuel within the container, to the air space above it, in its passage to the pipe connected to the engine intake. The combined cross sectional area of the perforations is preferably equal or thereabouts to the cross sectional area of the air inlet pipe connected to the chamber so that when a partial vacuum is created within the container by each intake stroke of the engine, the consequential in-rush of air to displace the partial vacuum will escape partly through each perforation. The number and positions of the perforations should preferably be such that the whole surface of the liquid fuel is violently agitated by the air that is passing upwardly through it. The container may be provided with an additional controllable air inlet for the purpose of weakening the mixture when necessary, the discharge orifice of such inlet pipe being situated above the level of the liquid fuel, whilst means are provided to prevent the possibility of the fuel in its liquid state from entering the pipe that is connected to the engine intake.

The invention may be applied in various forms but in order that it may be thoroughly understood a more detailed description will now be given and reference will be made to the accompanying sheet of drawings in which—

The figure is a perspective view of the invention in one of its simplest forms, a portion of the wall of the vessel in which vaporization is effected being broken away to expose the interior parts.

The container 10 in which vaporization is effected is provided with a flange 11 whereon is seated and secured in any suitable manner a lid or cover 12, an air tight joint between those two parts being made by any known means. Connected to the underside of the cover plate 12 is a chamber 13 which functions as a drying chamber and thereby prevents the fuel in its liquid state from entering the draw off pipe 14 which is connected to the engine intake. It is so constructed that should any

fuel in its liquid state enter the chamber it is conveyed to a point where it is immediately drained off but the gas that enters passes on to the draw off pipe. The cover plate 12 may form the top of the chamber 13 and internal communication between the pipe 14 and the chamber 13 be established through an orifice in the cover plate. At one side of and near the top of the chamber 13 is an orifice 15 to the inner side of which a pipe 16 is connected, such pipe being bent and extending downwardly to near the bottom of the drying chamber 13. It is preferable that the bottom of the drying chamber 13 be slightly inclined to a point immediately below the lower end of the pipe 16 so that should violent vibration cause the liquid fuel within the container 10 to enter through the orifice 15 it will pass down the pipe 16 and be discharged on to the lowest point of the bottom and immediately gravitate back into the container 10 through a drain pipe 17. It will be seen that the pipe 16 is the mechanical equivalent of a baffle plate and it will in some cases be advantageous to dispense with the pipe 16 and substitute therefor a plurality of baffle plates so that the gas entering the orifice 15 will be caused to take a serpentine course in its passage through the drying chamber to the pipe 14. Connected to and passing through the cover plate 12 are two air inlet pipes 18 and 19 the lower end of the former terminating at a point about midway between the ends of the vessel whilst the lower end of the latter terminates in an orifice in the top of a flat air distributing chamber 20. The top of the chamber 20 is provided with a number of perforations 21. The horizontal cross sectional shape of the air distributing chamber 20 is such that whilst it may lie upon or close to the bottom of the container 10 a space will be provided to enable a suitable float chamber 22 to be also seated upon or lie close to the bottom of the container 10. The float chamber 22 may be of any suitable known construction adapted to maintain the liquid fuel within the container 10 at a predetermined level, the inlet pipe 23 passing through the bottom of the container 10 and being connected directly or indirectly to a liquid fuel supply tank. For strengthening purposes the pipes 18 and 19 may pass through orifices in and be rigidly secured to a bracket 24 which is fixed to the side of the chamber 13. The pipe 18 is preferably closed at its lower end and provided with a number of perforations 28, through which air will issue radially and be thereby more thoroughly mixed with gas contained in the space above the liquid fuel within the container 10. The pipe 18 may be dispensed with and other means employed for the purpose of reducing the richness of the gas that passes into the pipe 14. Each of the pipes 18 and 19 may be controlled by suitable valves 25 and 26 respectively and any con-

venient known means may be adopted for operating these valves either separately or conjointly.

The pipe 14 will be provided with one or more back pressure valves 27 to obviate the risk of fire or explosion caused by back firing and as an additional precaution against such happenings, the vessel 10 may be provided with a relief valve 29, and another relief valve will of course be interposed between the valve 27 and the engine intake.

I claim:

1. A carburetor comprising a container for liquid fuel, a perforated air distributing chamber within the container, an air inlet pipe having one end connected to the air distributing chamber, the other end being controllably open to atmosphere, a float valve for maintaining the liquid fuel at a level above the air distributing chamber, a drying chamber having an orifice through which the mixture from the container may enter, a pipe connected to the orifice in the drying chamber and extending downwardly within and to near the bottom of the drying chamber, a gas draw off pipe connected to the drying chamber, and means for draining said drying chamber.

2. A carburetor comprising a container for liquid fuel, a perforated air distributing chamber within the container, an air inlet pipe having one end connected to the distributing chamber, the other end being controllably opened to the atmosphere, a float valve for maintaining the liquid fuel at a level above the air distributing chamber, a second air inlet conduit, one end of which is controllably opened to the atmosphere, the other end terminating at a point above the level of the liquid fuel within the container, a drying chamber having an orifice through which the mixture from the container may enter, a conduit connected to the orifice in the drying chamber and extending downwardly within and near the bottom of the drying chamber, a mixture outlet conduit connected to the drying chamber, and means for draining said drying chamber.

In testimony whereof, I have this fifteenth day of December, A. D. 1927 signed my name to this specification.

EDWARD HENRY PHILLIPS.
